UNITED STATES PATENT OFFICE.

WILLIAM C. FORD, OF BROOKLYN, NEW YORK.

IMPROVEMENT IN SUPPLYING HEATED AIR TO BOILER-FURNACES.

Specification forming part of Letters Patent No. 170,164, dated November 23, 1875; application filed September 29, 1875.

To all whom it may concern:

Be it known that I, WILLIAM C. FORD, of Brooklyn, in the county of Kings and State of New York, have invented certain new and useful Improvements in Steam-Boilers; and I do hereby declare the following to be a full, clear, and exact description of the same, reference being had to the annexed drawing, making part of this specification, in which—

Figure 1 is a vertical longitudinal section through an ordinary locomotive-boiler, with my improvement applied thereto; Fig. 2, a horizontal longitudinal section through said boiler, showing the application of said invention; and, Fig. 3, a transverse section through said boiler on the line *xx*, viewed from the rear end of the boiler.

The object of my invention is, first, to perfect the consumption of fuel in the furnace of steam-boilers, and of the gases developed in the process of combustion; second, to avoid the necessity of delivering the exhaust steam from a locomotive-engine in the smoke-pipe of the boiler to increase the draft of the furnace.

And my invention consists, first, of certain devices applied to a boiler, by which a stream of hot air is delivered upon the surface of the fire to perfect the combustion of the fuel-gases; second, of certain improved devices applied to a steam-boiler, by which a stream of hot air is drawn down around the smoke-pipe, and thrown upon the surface of the fire in the boiler-furnace by the motion of the boiler, or of the engine or vehicle which carries the boiler; third, of certain improved devices applied to the boiler of a steam-engine, by which a stream of air is created, drawn down and thrown in the furnace by the motion of the boiler, and heated by the waste or escaping heat of the fire on its passage to the furnace.

The drawing shows the application of my invention to the locomotive-boiler, though it is applicable to stationary boilers especially, also, if means be provided either through the agency of a blower, or other means well known in the arts to draw the air down around the smoke-pipe through the superheating-pipes, and force or draw it into the furnace upon the surface of the fire.

A practical method of applying the invention to the ordinary locomotive-boiler is as follows, reference being had to the drawing:

Let the boiler be made in the ordinary form, as shown in the drawing, in which the fire-box is shown by *A*, the grate-bars by *H*, the tubes by *B*, the shell or water space by *E*, the smoke-box by *C*, and the smoke-pipe by *F*. These are parts of the ordinary locomotive-boiler, and in almost the usual form, with the exception of the smoke-pipe, which in this case is incased in a funnel-shaped air-receiving pipe, shown by *c*, made larger than the smoke-pipe, by which there is left an annular space between the two pipes, as shown by *c*. This air-receiving pipe is fitted upon an air-chamber shown by *c* in Fig. 2 of the drawing, the smoke-pipe passing down through the air-chamber to the smoke-box in which it is located.

To the air-chamber there is connected a series of small tubes or pipes, *a a a a*, which pass through the flues of the boiler to the fire-box *A*, and connect upon a pipe or chamber, *b*, located in the top of the fire-box over the fire, in the best manner to most effectually expose it to the heat of the furnace.

Into the heating pipe or chamber *b* there are inserted two or more pipes, *d d*, leading to the outside of the boiler-front, as shown in Fig. 2. The out ends of these pipes are fitted with valves *f f*, and are connected to small pipes *e* leading into the front of the furnace.

The air-pipe *c*, it will be seen, is fitted with a funnel-shaped nozzle, the capacity of which may be increased should it be necessary to supply the required amount of air, by multiplying the nozzles, as shown by *h* and *i*, though it is thought that one nozzle will be sufficient. But the shape must, of course, be modified with reference to catching the air when the pipe is in motion, or in the case of stationary engines, when the wind blows from any direction.

The operation is as follows: The air, when the pipe is in motion, is forced down through the receiving-nozzle to the chamber *C*, from whence it passes through the tubes *a* to the pipe or chamber *b*, and from thence through

the pipe *d* and *e* into the furnace upon the top of the fire, the supply being regulated by the valves *ff*.

It will be seen that the air begins to heat from the time it strikes the smoke-pipe, and continues to increase in temperature until it strikes the fire, where it enters in combination with the hot gases of the fuel, and becomes itself a part of the fire it is intended to intensify.

The leading idea of this invention is, by improved means, to increase or intensify the heat of the furnace by discharging upon the surface of the fire a stream of highly-heated air, to combine with the gases of the fuel in combustion upon the top of the fire.

By the arrangement of the smoke-stack shown in the drawing the engine can still exhaust the smoke-pipe in case of need, though it is thought that the heat and draft of the

furnace under this system will be sufficient without it, by which the noise and dirt occasioned by the blast in the smoke-pipe can be avoided.

Having now described the nature of my invention, and the means of carrying the same in practice, I claim to and desire to secure by Letters Patent—

In combination with a locomotive or stationary steam-boiler, a superheater, consisting of a flue formed around the smoke-pipe, and connected to a series of pipes arranged in the heating surface and furnace of the boiler, substantially in the manner described, for the purpose specified.

WM. C. FORD.
